CLAIM

The ornamental design for a camera, as shown and described.

DESCRIPTION

This application incorporates by reference in its entirety each of the following U.S. design patent application Ser. Nos., filed on Jun. 26, 2018: 29/654,658, titled “Aerial Vehicle”29/654,662, titled “Battery”29/654,665, titled “Camera With Gimbal”

FIG. 1 is a top front perspective view of a camera showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the camera that form no part of the claimed design.

1 Claim, 4 Drawing Sheets
